UNITED STATES PATENT OFFICE

FRANK J. HINDERLITER, OF TULSA, OKLAHOMA, ASSIGNOR TO HINDERLITER TOOL COMPANY, OF TULSA, OKLAHOMA, A CORPORATION OF OKLAHOMA

OIL-WELL FISHING TOOL

Original application filed May 25, 1927, Serial No. 194,015. Divided and this application filed September 28, 1929. Serial No. 395,843.

My invention pertains to rotary mechanism for use in connection with the drilling of oil wells and more particularly to a method of and an apparatus for removing rotary disks, cones, cutters, broken pieces of fish tail bits and the like from a well in which they have broken off the tool or bit.

The present invention constitutes divisional subject matter taken from applicant's co-pending patent application, Serial No. 194,015, filed May 25, 1927.

In the drilling of an oil well or the like quite frequently the drill bit or cutter is broken and the fragments of the same gravitate to the bottom of the well. Obviously, these fragments of metal interfere with the further drilling of the well and may result in the breaking or damaging of additional tools. It is, therefore, usually essential that they be removed before the drilling operation is continued.

An object of this invention is to provide a method of and an apparatus for fishing these metal fragments broken off the drilling tools from the well.

Another object of my invention is to provide a fishing tool for use in connection with oil wells, adapted to be rotated in the bottom of the well to force and thread the tool fragments upwardly, and having hydraulic means for facilitating the rotation of the tool and for assisting the tool in forcing the broken tool fragments upwardly out of the bottom of the well.

In accordance with the general features of my invention, I provide a rotary cylindrical tool having its lower end formed into a bit-like member. Positioned in the tool and extending downwardly through it is a mandrel member for discharging a hydraulic jet through an opening disposed at the extreme lower end of the bit-like member. The shape of the bit-like member is such that it will gradually convey the broken tool fragment upwardly until it is in a position to gravitate into the interior of the fishing tool. Thereafter the tool may be withdrawn upwardly from the well and the metal fragment therein may be removed.

Of course, it is to be understood that al-

though my invention is especially designed for use in the drilling of oil wells, it is not to be thus limited, for, obviously, it could be used in other capacities without deviating from the features of my invention.

Other objects and advantages of my invention will more fully appear from the following detailed description taken in connection with the accompanying drawing which illustrates a single embodiment thereof and in which:

Figure 1 is an elevation of one form of my invention;

Figure 2 is a sectional view partly in elevation taken on substantially line II-II of Figure 1, looking in the direction indicated by the arrows;

Figure 3 is an end view taken at the bottom of the device as shown in Figure 2;

Figure 4 is a sectional view taken on substantially line IV-IV of Figure 2, looking downwardly;

Figure 5 is a sectional view taken on the line V-V of Figure 2;

Figure 6 is a sectional view taken on the line VI-VI of Figure 2; and

Figure 7 is a sectional view taken on the line VII-VII of Figure 2, looking in the direction indicated by the arrows.

In the drawings:

The form of my invention illustrated in the accompanying drawings is particularly adapted for use in wells where it is found that the earth at the bottom of the well is relatively hard.

The device comprises essentially three parts, namely, the bit 50, an intermediate sleeve 51 and the top 52. Both the bit 50 and the top 52 are threaded into the ends of an intermediate sleeve 51.

The top 52 includes a cylindrical opening 53 threaded at its upper end 54. The lower end of the top 52 is reduced at 55 forming a shoulder 56. This reduced end 55 is threaded at 57 onto the upper end of the intermediate sleeve 51. The shoulder 56 of top 52 is adapted to abut the upper end of the sleeve 51. The threaded opening 54 of the device is adapted to have secured therein the lower end of a suitable string of fishing tools for lower-

ing the tool of my invention into a well or the like.

The outer periphery of sleeve 51 is provided with a helical thread 58. This helical thread 58 is disposed in alignment and in communication with the helical thread 59 on the upper end of the bit 50. One side of the sleeve 51 is provided with a slot 60 through which the broken drill parts are adapted to enter the interior of the device.

The upper end of bit 50 is provided with a reduced portion 61 and a shoulder 62 adapted to abut the lower end of sleeve 51. This reduced end 61 is threaded into an opening 63 in the lower end of sleeve 51. From this it will be readily evident that both the top and bit are readily detachable from the intermediate sleeve 51.

Positioned within the bore of sleeve 51 is a mandrel or tubular member 65 through which a stream of water is conveyed from the string of fishing tools connected to the tool of my invention to the bit-like member 50. The upper end of this member 65 is provided with a flange or head 66 which constitutes a closure for the annular opening 53 and top 52. Also, if it is so desired the head may be provided with a number of relatively small openings 67 through which wires may be inserted for the purpose of moving the mandrel member 65 bodily upward out of the top 52.

The lower end of the mandrel member 65 extends into an opening 68 in the reduced end 61 of bit 50. This lower end of the member 65 is disposed in axial alignment with the opening 70 which extends clear through the bit 50.

The bit 50 has a pair of helical grooves 71 of a sufficient pitch and lead to carry any material entering therein up to the helical thread 59. The lower end of the bit, as shown in Figures 1 and 3, is substantially straight as indicated at 72. This straight portion has a diameter substantially equal to that of the sleeve 51. Also, it is to be noted that the straight edge 72 of bit 50 may be provided with a cutting surface 73.

The operation of this tool of my invention is briefly as follows:

A rotary member is threaded into the upper end 54 of opening 53 in the top 52 and the device is then lowered into the well. The mandrel 65 in this device of my invention performs the function of conducting a jet of water from the string of fishing tools into the drilling member or bit 50. This jet passes through the axial opening 70 in the bit 50 and is discharged at the lower end of the bit into the bottom of the well. It will be evident that this water will materially aid the bit in the drilling operation.

When the bit 50 strikes the bottom of the well, the device is actuated to revolve the bit. Obviously, by revolving the bit 50, the dirt at the bottom of the well will be drilled up

wardly along the grooves 71 into the helical threads 59 and 58. As the dirt moves upwardly it carries with it the broken drill parts which are to be removed from the well. These parts, after leaving the grooves 71 in the bit 50, come into engagement with the helical threads 59 and 58, which threads carry the part upwardly to a position opposite the slot 60. After the drill parts reach this position, they will obviously gravitate into the interior of the sleeve 51. Thereafter the rotation of the device may be arrested and the device may be withdrawn bodily from the well. As previously pointed out, the advantage of the drill or bit 50 at the lower end of the sleeve 51 is that it will dig its way into the earth should the earth be relatively hard or should the bottom of the well present a relatively flat surface to the action thereof.

Now, it is of course to be understood that although I have illustrated and described in detail the preferred form of my invention, the invention is not to be thus limited, but only in so far as defined by the scope and spirit of the appended claims.

I claim as my invention:

1. In combination, a tool for removing broken drill parts and the like from a well, a member formed to be lowered to the bottom of the well and having a pocket for receiving a broken drill part, means connected with said member for causing the part to crawl upwardly alongside said means into said pocket and a bit-like member connected to the lower end of said means for displacing said part from the bottom of the well and for conveying it to a position where it can be acted upon by said means.

2. In combination, a tool for removing broken drill parts and the like from a well, a member formed to be lowered to the bottom of the well and having a pocket for receiving a broken drill part, means connected with said member for causing the part to crawl upwardly alongside said means into said pocket and a bit-like member connected to the lower end of said means for displacing said part from the bottom of the well and for conveying it to a position where it can be acted upon by said means, said bit-like member including a helical groove in which the part is adapted to be conveyed and having its uppermost end terminating adjacent said means.

In testimony whereof I have hereunto subscribed my name at Tulsa, Tulsa County, Oklahoma.

FRANK J. HINDERLITER.
